UNITED STATES PATENT OFFICE.

HENRY WILLIAM MOHANY, OF MOUNT HOORB, WISCONSIN, ASSIGNOR OF TWO-THIRDS TO HALVAR NELSON AND HENRY J. EGGERS, BOTH OF SAME PLACE.

LIFTING-JACK.

SPECIFICATION forming part of Letters Patent No. 297,705, dated April 29, 1884.

Application filed March 4, 1884. (No model.)

To all whom it may concern:

Be it known that I, HENRY W. MOHANY, a citizen of the United States, residing at Mount Horeb, in the county of Dane and State of Wisconsin, have invented a new and useful Lifting-Jack, of which the following is a specification, reference being had to the accompanying drawings.

My invention relates to a device for lifting railroad-tracks and other heavy objects; and it has for its object to provide a device of this character which shall be capable of raising or lifting heavy objects with but little exertion on the part of the operator.

15 A further object of the invention is to provide a device for this purpose which shall be cheap and simple in its construction and durable in use.

With these ends in view the invention consists in the improved construction and combinations of parts hereinafter fully described, and pointed out in the claims.

20 In the drawings, Figure 1 is a perspective of a jack constructed in accordance with my invention. Fig. 2 is a vertical section of the same, and Fig. 3 is a transverse section on the line *xx* of Fig. 2. Fig. 4 is a perspective view of the lever-disk detached.

25 In the accompanying drawings, in which like letters refer to corresponding parts in the several figures, A represents a suitable upright or support, to the upper end of which is secured a jack-head or bracket, B. This jack-head or bracket B is provided with an extended slot or opening, *a*, in which works the operating-lever, as will be presently described. The jack-head or bracket B is also provided with an enlarged opening, which forms the seat or bearing for a roller, C, which, 30 like the bracket B, is constructed of metal. This lifting disk or roller is provided with a recess for the reception of a lever, which works in the slot or opening *a* of the bracket B. Upon this lifting disk or roller, which has 35 bearing in the opening of the bracket or jack-head B, are secured downwardly-extending arms D, which are pivotally connected to said roller. Upon the lower ends of these arms is

provided a transverse bolt, upon which is pivotally secured one end of a lifting portion, E, 50 the lower end of which is provided with an angular piece to engage a railroad-rail; or it may be provided with other suitable lifting devices which will act with equal efficiency.

Upon each side of the upright A is secured a bracket or handle, F, which are for the purpose of transporting the jack from place to place.

H represents a bar or lever for raising or operating the roller, and is adapted to be inserted within the opening thereof.

The operation of my device is as follows: The angular end of the portion E is inserted under the rail, and the lever inserted within the opening or the recess of the roller, which is 65 then at the forward end of the slot of the bracket A, and upon the lever H being pushed downwardly or rearwardly the roller is caused to revolve until the rail has been sufficiently raised or the end of the slot has been reached, 70 which brings the arms on a direct line with the axis of the roller, thus holding the rail in a raised position without any power being exerted.

It will be obvious from the above description that my improvement is simple in its construction, and that by its use weighty objects may be raised with but little power or force in operating the lever.

Having fully described my invention, what I claim as new, and desire to secure by Letters Patent, is—

1. The combination, with a suitable upright or standard, of a jack-head secured to the upper end thereof, said jack-head being provided with a slot extending around a portion of its circumference and provided with an enlarged opening, substantially as set forth.

2. The combination, with a suitable upright or standard provided at its upper end with a jack-head or bracket having a slot and opening, as shown, of a roller having bearing in said opening, substantially as set forth.

3. The combination, with a jack-head or bracket supported upon a suitable standard, and provided with a slot and opening, as

shown, of a roller having bearing in said opening, and provided with a recess or slot for the reception of a bar or lever, substantially as set forth.

5 4. The combination, with a jack - head or bracket supported upon a suitable standard, and provided with a slot and enlarged opening, as shown, of a roller bearing in said opening, and provided with a recess or slot for the 10 reception of a bar or lever, and arms connected to the sides of said roller, said arms being pro-

vided at their ends with a pivoted portion having an angular end, substantially as set forth.

In testimony that I claim the foregoing as 15 my own I have hereto affixed my signature in presence of two witnesses.

HENRY WILLAM MOHANY.

Witnesses:

HENRY J. EGGER,
HALOVOR NELSON.
